UNITED STATES PATENT OFFICE.

HENRY STOCKMAN, OF PHILADELPHIA, PENNSYLVANIA.

LAST-SUPPORTING JACK.

SPECIFICATION forming part of Letters Patent No. 340,063, dated April 13, 1886.

Application filed November 25, 1885. Serial No. 183,956. (No model.)

To all whom it may concern:

Be it known that I, HENRY STOCKMAN, a citizen of the United States, residing at Philadelphia, in the county of Philadelphia and 5 State of Pennsylvania, have invented certain new and useful Improvements in Jacks, of which the following is a specification, reference being had therein to the accompanying drawings.

10 My invention relates to last - supporting jacks for shoe-makers' use, and has for its object the provision of means for throwing the jack-body and its contained last into different positions for convenience to the operator, and 15 in means employed to secure it from displacement therefrom.

To these ends the invention comprises, in connection, a sub-base secured to the bench or table, a base that supports the last-holding 20 jack, a hinged connection between the base and sub-base which allows the base to be turned either to the right or left, and means for holding said base in fixed position at any desired point.

25 In addition to the above-described adjustment, I provide that the jack-body shall be loosely connected to the base, so as to turn freely upon a central pivot thereon in a plane of motion at right angles to the plane of motion of the base without reference to the position occupied by the sub-base, and means for securing said jack-body at different desired points of adjustment upon the base.

30 The invention further contemplates the provision of means which, used in connection with the jack - body, allow a last to be instantly placed in position upon or removed from said jack-body, and in means for holding the last securely in position when in use.

40 The invention above set forth is hereinafter fully described, and specifically pointed out in the claims.

In the accompanying drawings, which form a part of this specification, Figure 1 is a side 45 elevation of a jack embodying my improvements. Fig. 2 is an elevation of the opposite side of the jack. Fig. 3 represents an end elevation thereof. Fig. 4 is a longitudinal section through the jack and its attachments. Fig. 50 5 is a transverse section of Fig. 1, showing the base and its attached jack-body turned to the right. Fig. 6 is a similar sectional view, the

base and its attached jack-body turned to the left. Fig. 7 is a top plan view of the sub-base. Fig. 8 is a bottom plan view thereof. Fig. 9 55 is a top plan view of the base. Fig. 10 is a bottom plan view thereof. Figs. 11 and 12 are detail views of parts of the jack-body; and Figs. 13 and 14 represent modified forms of the pivoted supporting-bar of the base. 60

Referring to the drawings, in which similar letters of reference denote similar parts, A designates the sub-base, consisting of a thin plate, *a*, of metal, provided at its side and end edges with downwardly-projecting flanges *a'*, 65 that bear upon the bench or table.

a' designates a slot formed at the middle of the sub-base for the passage of a locking-bar, B, pivoted to the base, as hereinafter described.

70 *a'* *a'* designate lugs projecting from the lower surface of the sub-base at each side of the slot *a'*. I provide the lugs *a'* with screw-threaded apertures *a'*, that receive the screw-threaded inner end of a rod, C, that extends 75 thence below the part *a* through the flange *a'*, and is provided upon its outer end with a winged head, *c*, to operate the rod. The rod C serves to secure the bar B at different desired points within the slot *a'*; and to this end 80 the inner end of the rod may either bear against the bar B or said bar may be perforated to receive the end of the rod, as shown in Fig. 14.

85 *a'* *a'* designate apertured lugs projecting from the upper surface of the sub-base, at one side thereof, to which is pivotally connected by a rod, *d*, one end of a frame, D, the opposite end of which is pivoted to the base E. The frame D is in length equal to the width of 90 the sub-base, and consists in side rails, *d'*, and transverse rails *d''*. Apertured lugs *d'*, formed on the ends of said frame afford passage to the rods by which it is connected to the base and sub-base, respectively.

95 E designates the base, consisting of a thin plate, *e*, of metal, provided at its edges with a downwardly-projecting flange, *e'*, which rests upon the sub-base.

100 *e'* designates an aperture formed at the middle of the base, to receive the shank of a screw-threaded bolt, F, which secures the jack-body to the base, as hereinafter described. The head *f* of the bolt F is square in cross section,

is held within a socket, e^3 , formed by flanges e^4 upon the lower surface of the base at each side of the aperture e^2 , and is provided with downwardly-projecting lugs f' , between which is pivoted the upper end of the adjusting-bar B.

e^5 designates strengthening-ribs formed upon the lower surface of the plate e. The flange e' of the base is cut away at its sides $e^6 e^7$, for the reception of the frame D, one end of which is pivoted by a bolt, e^8 , within the cut-away portion e^9 of the flange e' .

By reference to Figs. 5 and 6 it will be observed that the above-described hinged connection between the base and sub-base permits the turning of said base either to the right or left, the respective ends of the frame D becoming in turn the pivotal point of the base.

I secure the jack-body to the base E in the following described manner, viz:

20 e^9 designates a circular rib formed upon the upper surface of the base E, and this rib has for its center the aperture e^2 , and fits into a circular groove, g , formed in the bottom of the jack-body G. The groove g has for its center 25 an aperture, g' , formed through said jack-body at the middle thereof. The upper threaded end of the bolt F projects through the aperture g' , and through a boss, g^2 , projecting from the upper surface of the jack-body about said 30 aperture. The boss g^2 is provided upon its upper surface with cam-faces g^3 , which engage similar cam-faces, h , formed upon the lower surface of the apertured head of a cam-lever, H, placed upon the upper end of the bolt F.

35 F' designates an adjusting-nut upon the bolt above the lever.

By operating the lever H the jack-body may be firmly secured at any point of its plane of motion, as will be readily understood.

40 The jack-body G comprises a base, G^1 , a toe-standard, G^2 , having a ridge, g^4 , at its lower end, and a fixed heel-standard, G^3 , having a rounded upper end, g^5 , and a transverse aperture, g^6 .

45 I designates a swinging heel-standard having a bifurcated lower end, the parts i of which extend at each side of the standard G^3 , and are provided with square apertures i' , to receive the squared portion of a lever, J, journaled 50 in the aperture g^6 of the standard G^3 . The upper end of the swinging standard I is provided with an aperture to receive a removable pin, i^2 , which is held in place by a set-screw, i^3 .

The lever-arm J is provided at its free end 55 with a slot, through which projects from the jack-body a screw-threaded bolt, K, whereby any desired degree of tension may be imparted to a spiral spring, K', interposed upon bolt K, between the thumb-nut k and lever J.

60 The spring K' operates to hold the free end of the lever J against the upper surface of the jack-body, and through said lever the upper end of the swinging standard forward in the position shown in Fig. 1, whereby the toe 65 of a last placed upon said standard will bear firmly upon an adjustable toe rest or block, L, having a bifurcated lower end, the parts l

of which extend at the sides of and engage with vertical grooves m , formed in the sides of a casting, M, having a sleeved lower end, m' , 70 which fits upon the toe-standard G^2 , and a slot, m^2 , that engages the rib g^4 at foot of said standard.

If desired, the upper end of the standard G^2 may be apertured, as shown in Fig. 4, to 75 receive a removable pin similar to that employed in connection with the swinging standard I, or said standard may be enlarged longitudinally and operate in lieu of the casting M, and be provided with a series of apertures to receive an adjustable toe-rest.

I do not limit myself to the exact construction of parts herein shown and described, as I am aware that various modifications may be made therein without departing from the 85 spirit or sacrificing the advantages thereof—as, for instance, a spring-pin may be used to secure the bar B in lieu of the bar C.

No claim is broadly made herein for the construction of the lever J with the swinging 90 heel-support I; as such matter is broadly claimed in my application filed September 29, 1885, Serial No. 178,571.

I claim—

1. A last-holding jack having a sub-base 95 secured to a suitable support, a base mounted thereon, and a frame interposed between and hinged, respectively, to the base and sub-base, substantially as described.

2. In a last-holding jack, a sub-base secured 100 to a suitable support, a base mounted thereon, a frame interposed between and hinged, respectively, to said base and sub-base, and a pivoted holding-bar, substantially as described.

3. In a last-holding jack, a sub-base secured 105 to a suitable support, a base mounted thereon, a frame interposed between, extending transversely of and hinged at its opposite ends to the base and sub-base, respectively, a holding-bar pivoted to the base and extending through 110 the sub-base, and a locking-bar, substantially as described.

4. In a last-holding jack, a sub-base secured 115 to a suitable support, a base mounted thereon, and a frame interposed between and pivotally connected at its opposite ends to the base and sub-base, in combination with a jack-body having its plane of motion at right angles to the plane of motion of the base, substantially as described.

5. In a last-holding jack, and in combination, a sub-base secured to a suitable support, a base mounted thereon, a frame interposed between and pivotally connected at its opposite ends to the base and sub-base, respectively, a holding-bar pivoted at its top to the base, and a last-holding jack-body having toe and heel supporting standards and locking-lever, substantially as described.

6. In a last-holding jack, a sub-base secured 130 to a suitable support and provided at its middle with an aperture to receive the base-holding bar, and lugs to receive a locking-rod, in combination with a base having an apertured

middle to secure the holding-bar, and a frame interposed between and hinged at its opposite ends to the base and sub-base, respectively, substantially as described.

5 7. The combination, in a last-holding jack having a plane of motion at right angles to the plane of motion of its base and provided with a toe-standard and apertured heel-standard, of a removable swinging heel-standard having a bifurcated lower end, its operating-lever, which determines the pressure, and the tension-spring, substantially as described.

10 8. In a last-holding jack, the combination of a jack-body having a fixed heel-standard provided with a transverse aperture, with a swinging heel-standard having a removable last-receiving pin, a bifurcated lower end having apertures, and a spring-controlled lever which determines the pressure with which the 15 last is held in position, substantially as described.

20 9. In a last-holding jack, a jack-body provided with a fixed toe-supporting standard

having an adjustable toe-support, a fixed heel-supporting standard having a swinging heel-support, and a tension-regulating lever, in combination with a base, a sub-base, a frame interposed between and hinged at its opposite ends to the base and sub-base, respectively, and the base holding-bar and locking-rod, substantially as described. 25 30

10 10. In a last-holding jack, and in combination, a sub-base, A, having upwardly-projecting lugs on one side thereof, a hinged connection, as D, pivoted at one end to said lugs and 35 at its opposite end to the opposite side of the base E, a holding-bar, B, a locking-rod, C, a centrally-pivoted jack-body, G, having cam-face g, and a cam-lever, H, substantially as described. 40

In testimony whereof I affix my signature in presence of two witnesses.

HENRY STOCKMAN.
